UNITED STATES PATENT OFFICE.

FREDERICK J. STEINBACH, OF CHICAGO, ILLINOIS.

CONCRETE-DRILL.

1,060,647.

Specification of Letters Patent.

Patented May 6, 1913.

Application filed May 17, 1911. Serial No. 627,717.

To all whom it may concern:

Be it known that I, FREDERICK J. STEINBACH, a citizen of the United States, and a resident of the city of Chicago, county of Cook, and State of Illinois, have invented certain new and useful Improvements in Concrete-Drills, of which the following is a specification.

My invention relates to improvements in rock or concrete drills and has for its object the provision of a manually operated drill of this character which shall be simple of construction and efficient in operation.

Other objects will appear hereinafter.

With these objects in view my invention consists in the novel construction and arrangements of parts all as will be herein-after more fully described and particularly pointed out in the appended claims.

My invention will be more readily understood by reference to the accompanying drawings forming a part of this specification, and in which,

Figure 1 is a side elevation of a rock or concrete drill embodying my invention, Fig. 2 is a vertical longitudinal section of the drill, parts being shown in elevation at right angles to that shown in Fig. 1, and Fig. 3 is a detail sectional elevation showing a cushioning means employed in the device.

The preferred construction of my invention as illustrated in the accompanying drawings comprises a barrel or cylinder 1 carrying a crank shaft hanger 2 and a handle 3 at the upper most end thereof. A crank shaft 4 is mounted for rotation in the crank hanger 2, and the crank pin 5 of said crank shaft is adapted to transmit reciprocatory motion to a plunger 6 by means of a connecting rod 7 which converts rotary into rectilinear motion as is understood by those skilled in the art. The connecting rod 7 has a plain bearing connection with the crank pin 5, but a cushioning means is provided in the connection of said connecting rod with the plunger 6. The latter connection comprises a diametrically disposed pin 8 passing through the plunger 6 and a slot 9 provided at the lower end of the connecting rod 7. The pin 8 thus supports the plunger 6, since the same is normally seated at the lower end of the slot 9, the weight of said plunger normally holding the pin 8 to its seat. The cushioning means comprises a block 10 resting upon the pin 8 and a compression helical spring 11 interposed between said

block and the upper end of the slot 9, the construction being such that quick upward movements of the plunger 6 will be absorbed by the spring 11, thus preventing the transmission thereof to the crank pin 5 and the crank operating means. The crank 4 is provided with an elongated end 4' which carries at the outer end thereof a spur pinion 12 arranged in mesh with and driven by a spur gear 13 as clearly shown in Figs. 1 and 2. The driving gear 13 is rotatably mounted upon a stud 14 projecting laterally from the cylinder 1, there being a handle crank 15 secured to one side of said gear and a handle 16 carried by the outer end of said handle crank. Thus the manner in which the plunger 6 is reciprocated is evident, the main operation of the device being the turning of the handle 16. A reduced end 17 is provided on the cylinder 1 and to this end is secured a cylinder extension 18 which forms a guide for a reciprocatory tool holder 19, the holder being provided with a socket 20 in which a suitable tool such as a drill 21 is detachably secured by means of a setscrew 22. The principal movement of the drill 21 in the cutting operation thereof is a short vertical reciprocatory movement produced by the impact of the plunger 6 on the top 23 of the tool holder 19. It is obvious from the construction described that the plunger 6 delivers to the top 23 a quick succession of blows thereby rendering the cutting rapid and efficient. In order to return the tool holder 19 to the normal or elevated position after being struck and depressed by the plunger 6, a compression helical spring 24 is positioned inside of the cylinder extension 18 abutting at one end a shoulder 25 provided in said extension and at the other a circumferential collar 26 which is located at the juncture of the top 23 and the main body of the tool holder 19. The action of the spring 24 is to normally hold the collar 26 in engagement with or in close proximity to the lower end 27 of the main cylinder 1. The tool holder 19 is thus in a position as to be readily depressed by the action of the plunger 6, the only resistance to such depression being the spring 24 and the cutting end of the drill 21 in the hole being formed. After the plunger 6 has delivered a blow to the top 23 of the tool holder 19 it rebounds and were it not for the cushioning spring 11 would transmit a jar or vibration to the handle 16 thus rendering the operation of

the latter disagreeable and tiresome to the operator.

In order to produce a perfectly round hole the drill 21 is rotated slowly by means of feeding mechanism to be presently described. This mechanism comprises an eccentric groove 28 which is formed in the inner surface of the driving gear 13 and adapted to transmit vertical reciprocatory motion to a rod 29 mounted in bearings 30 which project laterally from the main cylinder 1. The connection of the rod 29 with the eccentric groove 28 consists in a friction roller 31 mounted on a stud 32 formed integral or secured rigidly to said rod. The roller 31 thus travels in the groove 28 and causes a single depression of the rod 29 during a complete revolution of the gear 13. The vertical reciprocatory motion of the rod 29 is transmitted to a ratchet wheel 32 by means of a pivoted gravity-operated pawl 33 provided at the lower end of said rod, this action being clear by reference to Fig. 1. During a single downward stroke of the rod 29 the ratchet wheel 32 is moved a circumferential distance corresponding with the width of one or two of the teeth thereof, thus producing an intermittent motion. Formed integral with the ratchet wheel 32 and disposed on the inner side thereof is a bevel gear 34, said gear and ratchet wheel being rotatably mounted on a stationary laterally extending stud 35 formed integral with the cylinder extension 18. A cotter-pin 36 retains the ratchet wheel and bevel gear in position. Meshing with the bevel gear 34 and driven thereby is a bevel gear 37 arranged coaxially with the cylinder extension 18 and adapted to rotate on the lower end thereof. The bevel gear 37 is held in position with reference to the cylinder extension 18 by means of two semi-circular bands 38 which are secured to the periphery of the lower end of the cylinder extension 18 by means of screws 39 and are provided with inwardly extending flanges 40 for engagement with a peripheral groove 41 provided at the upper end of the bevel gear 37. From this construction the manner of mounting and operation of the bevel gear 37 is apparent. In order to transmit motion to the tool holder 19 for feeding the drill 21 a key 42 is provided in the bore 43 of the gear 37 which key projects into a longitudinal groove 44 formed in said tool holder, thus producing a splined connection of the latter with said bevel gear. In this manner the drill 21 is intermittently rotated during the vertical reciprocations thereof.

After a hole has been partially drilled, drillings and dust ordinarily accumulate therein and to prevent such accumulation the following pneumatic means is provided:

65 This means comprises a check-valve 45 ar-

ranged in communication with the space in which the plunger 6 operates, said check-valve being gravity-operated and permitting of free entrance of air to said space when a partial vacuum is formed therein by the upward movement of the plunger 6. At the beginning of the downward stroke of the plunger 6 the air drawn into the space below said plunger is imprisoned therein by the automatic closing of the check-valve 45 thus preventing its escape therethrough. Said air is forced through an outlet check-valve 46 arranged opposite the check-valve 45 and thence through a conduit 47 which discharges in a region adjacent the hole being drilled. The effect of the action as described is to clean the hole being drilled from all dust and accumulation of any kind.

The mode of the operation of the drill is as follows: The handle 3 of the device is held in one hand and the handle 16 rotated with the other, the drill 21 being properly positioned on the rock or concrete to be drilled. Then the handle 16 is rapidly turned which causes the drill 21 to reciprocate vertically in a rapid manner and to turn slowly by means of the feeding mechanism as above described. All shock or vibration which might be produced from the upward strokes of the plunger 6 is absorbed by the spring 11, the block 10 on which said spring abuts moving longitudinally in the slot 9 to effect this end.

A concrete drill of the construction set forth is compact and neat in appearance and efficient in its operation.

While I have illustrated and described the preferred form of construction for carrying my invention into effect, this is capable of variation and modification without departing from the spirit of the invention. I therefore do not wish to be limited to the precise details of construction set forth but desire to avail myself of such variations and modifications as come within the scope of the appended claims.

Having described my invention what I claim as new and desire to secure by Letters Patent is:

1. In a device of the class described, a barrel, a tool holder mounted for reciprocation in said barrel, means for imparting a blow to said tool holder, a beveled gear rotatably mounted on the end of said barrel and in splined engagement with said tool holder, a second beveled gear mounted upon said barrel but in mesh with the last mentioned gear, a rod mounted for reciprocation and on said barrel and operated synchronously with said blow imparting means, and a ratchet connection between said second beveled gear and the adjacent end of said rod, substantially as described.

2. In a device of the class described, a

barrel, a beveled gear at the end of said barrel provided with a hub having a peripheral groove, a pair of semicircular bands secured to the end of said barrel and each provided with an inturned flange engaging in said groove, a tool holder mounted for reciprocation in the end of said barrel and extending through said gear, a splined connection between said gear and said tool

holder, means for intermittently turning 10 said gear, substantially as described.

In testimony whereof I have signed my name to this specification in the presence of two subscribing witnesses.

FREDERICK J. STEINBACH.
